UNITED STATES PATENT OFFICE.

JOHN E. OSMER, OF OWOSSO, MICHIGAN, ASSIGNOR OF ONE-HALF TO JAMES M. JORDAN, OF PUNXSUTAWNEY, PENNSYLVANIA.

FORCE-FEED LUBRICATOR.

1,412,890.

Specification of Letters Patent. Patented Apr. 18, 1922.

Application filed January 12, 1920. Serial No. 350,788.

To all whom it may concern:

Be it known that I, JOHN E. OSMER, a citizen of the United States, residing at Owosso, in the county of Shiawassee and State of Michigan, have invented certain new and useful Improvements in Force-Feed Lubricators, of which the following is a specification.

The invention relates to lubricators of the type adapted to force oil into cylinders, passageways, steam chests and similar chambers which are under pressure of steam, air and the like.

The object of the invention is to provide a lubricator embodying an oil pump which is adapted to operate under all conditions to effectively supply oil to a point of consumption against the action of pressure fluid.

A more specific object of the invention is to provide improved means for controlling the flow of oil from the pump to the point of consumption.

A further object of the invention is to provide an oil pump in which a quantity of oil may be maintained under constant pressure sufficiently high to overcome the force of pressure fluid at the point of consumption.

The objects of the invention thus generally stated, together with other and ancillary advantages, may be attained by the construction and arrangement illustrated in the accompanying drawings wherein Figure 1 is a fragmentary side elevation showing my improved lubricator applied to a steam engine. Fig. 2 is a vertical sectional view of the oil pump taken on the line 2—2 of Fig. 3. Fig. 3 is a horizontal section through the pump taken in the plane of line 3—3 of Fig. 2, a portion of the pump being shown in elevation. Fig. 4 is a horizontal section taken on line 4—4 of Fig. 2. Fig. 5 is a fragmentary sectional view of a check valve employed at the point of consumption.

Referring to Fig. 1 of the drawings, 1 is the steam chest of one of the cylinders of a locomotive and 2 the valve operating rod of the chest. 3 designates generally a pump constructed in accordance with my invention mounted upon the steam chest and operable by means of a suitable connection between a moving part of the engine, such as the valve operating rod 2, and an operating lever 4 of the pump. Herein such connec-

tion consists of a link 5 fixed to an arm 6 rigid with the valve operating rod 2. 7 and 7^a indicate discharge pipes leading from the pump to the opposite cylinders of the locomotive engine, only one of such cylinders being herein shown.

The pump 3 may be mounted in any suitable manner in a desired position relative to the actuating mechanism therefor, it being understood that the invention is not limited to the particular manner shown of applying the invention to a mechanism to be lubricated.

The pump proper comprises a casing having a main or supply chamber 8 and a high pressure chamber 9, said chambers being separated by a horizontal partition 10 between which and the wall of the casing forming the high pressure chamber are provided stays 11 for imparting strength thereto. The opposite side walls of the casing are made of increased thickness as shown at 12 (Fig. 3), and such enlarged portions of the side walls are provided with vertical bores to receive the cylinders of the pump. Preferably I employ a dual pump construction, comprising two plungers 13 operating in cylinders 14.

Each of the pump cylinders 14 comprises a tubular member of substantial length and small diameter, and is held in place by means of a set screw 15. Said plungers 13 are also made of substantial length, extending a substantial distance beyond the center of the cylinder. At its lower end each cylinder communicates by means of a passageway 16 therein and a port 17 in the wall with a valve chamber 18, the latter communicating by means of a port 19 with the high pressure chamber 9. In the valve chamber 18 is a ball check 20 adapted to be seated upon the end of the passageway 17 and normally held in position upon its seat by means of a spring 21 bearing between a pressure element 22 and a screw plug 23 entered in the wall of the casing.

For operating the plungers 13 I provide a rocker arm 24 pivoted at its center upon a pivot pin 25 carried by a pair of upstanding arms 26 on the upper wall of the pump casing. The plungers 13 are each pivotally connected to the opposite ends of the arm

24 by means of pivot pins 27; and rigid with the rocker arm 24 centrally thereof is the operating arm 4, the lower end of which is connected by means of the link 5 and arm 6 with the valve rod 2.

The reciprocation of the operating arm 4 and hence the up and down movements of the plungers 13 is arranged to draw oil from the oil chamber 8 and force it into the high pressure chamber 9. This is effected by the movement of the plungers 13 within the cylinders 14, and to permit such flow of oil to the cylinders 14 and thence to the chamber 9, I provide near the bottom of each chamber in each side wall of the case a duct 28, and registering with said duct a port 29 in the tubular member 14. It will be seen that upon the upward stroke of each of the plungers 13, oil will be drawn from the chamber 8 into the pump cylinders 14, and upon the downward movement of the plungers oil will be forced by way of the ports 17 and valve control passage 16 into the valve chambers 18, and thence by way of port 19, into the high pressure chamber 9.

Between the high pressure chamber 9 and the chamber 8 is interposed a relief valve designated generally by the numeral 30. This relief valve comprises a ball check valve 31 entered within a valve chamber 32 which may be formed within the chamber 8 integral with the partition 10. The ball check 31 is held seated upon the upper edge of a port 33 in said partition by means of a compression spring 34 bearing between a screw plug 35 entered in the valve casing 32 and a holding member 36 engaging with the ball. A port 37 in the side of the valve casing 32 establishes communication between the chamber 8 and the interior of the casing. By adjusting the nut 35 the spring 34 may be tensioned as desired, and in practice this tension is such that when the pressure of oil in chamber 9 reaches a predetermined point above that necessary to force oil to the point of consumption under pressure, oil will be permitted to escape from the high pressure chamber into the low pressure chamber by way of the relief valve 30.

From the high pressure chamber 9 the oil is conducted to the point or points of consumption and this may be effected in any preferred way. Preferably I utilize the plungers 13 to control the flow of oil from the high pressure chamber. To this end I provide a passageway 38 leading through each wall of the casing with a portion substantially S-shaped so as to be interrupted by the plunger 13; and said passageway has at one end a vertical portion 38^a connected with the chamber 9 and at its other end a horizontal portion 38^b connected with an outlet nozzle 39. The S-shaped portion of said passageway comprises vertical portions 38^c and 38^d on opposite sides of the pump

communicating at their opposite ends with the interior of the pump cylinder by means of suitable ports in the cylinder. In the plunger 13 is a passage 40 which is adapted in the movements of the plungers to successively establish communication between the portion 38^a of said passageway and the portion 38^c; between the portion 38^c and the portion 38^d; and between the portion 38^d and the portion 38^b. It will thus be seen that in the movements of the plungers oil from the chamber 9 will flow under pressure successively from one portion of the passageway to the next, as permitted by the port 40 in the plunger, until it finally arrives at the discharge nozzle 39 from whence it is conducted by means of the pipes 7 or 7^a to the point or points of consumption. By proportioning the size of the portions 38^c and 38^d of the passageway 38 it will be seen that the amount of oil which is discharged with each reciprocation of the arm 4 may be regulated as desired.

For the purpose of effectively preventing the leakage of oil into the pump cylinder from the passageway 38, I provide the plungers 13 in their central portions with a split tubular valve member 41. To this end the plunger proper is reduced in diameter in its lower portion sufficiently to accommodate the valve member 41, the latter being split as shown at 42. To hold said member against rotation upon the plunger, a dowel pin 43 may be employed and a nut 44 screw-threaded on the lower end of the plunger and held by means of a pin 45 serves to clamp the member 41 in position. Said member 41 is preferably made of spring steel so that it tends to effectively seal the ends of the passageway 38 opening into the cylinder 14.

The pipes 7 and 7^a leading from the pump are arranged to discharge into the chamber under pressure. Preferably I employ a check valve 46 at the discharge end of said pipes as shown in Figs. 1 and 5. Such valve may be of any suitable construction being preferably adjustable to permit of varying the degree of pressure upon the oil before permitting its discharge into the pressure chamber. Herein I have shown a valve casing 47 open at its lower end to receive a screw plug 48. The lower end of the casing 47 is adapted to be screw-threaded into a collar or flange 49 fixed upon the chest or chamber 1. The opposite end of the casing 47 is restricted in size and connected by means of a lock nut 50 with the pipes 7 or 7^a. A check ball 51 within the valve casing is held seated upon the inner end of the passageway 52 leading thereinto by means of a compression spring 53 bearing between the screw plug 48 and the holding member 54 engaging with the ball 51. The screw plug 48 has an aperture 55 therein communicating 130

with a port 56 opening into the chamber. It will be seen that by adjusting the screw plug 48 the degree of pressure to which it is necessary to bring the oil before it can be introduced into the compression chamber may be varied.

In practice the relief valve 30 between the high pressure chamber 9 and the supply chamber 8 of the pump is set at a somewhat

- 10 higher tension than the pressure of the fluid within the chamber 1, so as to maintain in the pressure chamber 9 at all times the oil under a sufficiently high pressure to overcome the pressure of the fluid in the casing 15 1; and the check valve 46 is so tensioned as to permit the discharge of oil into the chest 1 when the pressure in the chamber 9 rises above the pressure in the chest.

I would have it understood that while the 20 use of the circuitous passage 38 controlled by the plunger 13 is to be preferred, the invention is not thus limited but that other connections may be provided between the chamber 9 and the point of consumption wherein 25 the flow of oil is not controlled by the plungers 13. In this latter event, the check valve 46 is placed under a tension substantially equal to that of the relief valve 30 so that the flow of oil from the chamber 9 to the 30 point of consumption will be properly controlled.

It will also be understood that when the flow of oil is controlled by the plungers 13, the use of check valves in the discharge 35 passages 7 and 7^a are not essential, since the plungers are arranged to coact with the passageways 38 so as to regulate the quantity of oil discharged.

The upper ends of the pump cylinders 40 through which the plungers 13 extend may be closed by any suitable gland consisting of a packing 57 and a nut 58.

For the purpose of filling the chamber 8 I provide an opening 59 arranged to be closed 45 by a cap 60 which may be held in position by means of a rod 61 having a screw-threaded connection with the screw plug 35 of the relief valve 30. To provide an air vent for the chamber 8, the annular flange surrounding 50 the opening 59 and the cap fitting over said flange may be provided with grooves 62 and 62^a.

The pump operating mechanism is shown (Fig. 3) as located centrally of the pump 55 casing; and to accommodate the operating lever 4, the casing is provided with an inner shell 63 providing a space 64 of sufficient size to permit of the movements of the lever. For this purpose also, the filling opening 59 60 and the relief valve 30 are located at one side of the center, as shown in Fig. 3.

It will be apparent that I have provided a force feed lubricator of a very practical character. A quantity of oil is maintained 65 at a sufficiently high pressure at all times to

overcome the pressure at the point of consumption; and the flow of oil from the pump is at all times properly controlled.

To insure that the oil shall be maintained in a fluid condition in cold weather, a steam 70 passageway 65 is provided within the pump casing. This passageway may be connected with a suitable source of steam supply (not shown).

I claim as my invention: 75

1. A lubricator comprising, in combination, a pump having a low pressure or supply chamber, a high pressure chamber, means establishing valve-controlled communication between said chambers, means 80 operable to draw oil from the supply chamber and force it to the high pressure chamber, means operatively associated with the mechanism to be lubricated adapted to actuate the pump, and a discharge passage 85 leading from the high pressure chamber, said passage being associated with and controlled by said oil drawing means.

2. A lubricator comprising, in combination with a chamber under fluid pressure, a 90 pump operable to force oil to said chamber comprising a casing having a low pressure chamber and a high pressure chamber, a cylinder communicating with both of said chambers, a piston in said cylinder operable to draw oil from one of said chambers and force it into the other one of said chambers, and a connection between the high pressure chamber and the chamber under 95 fluid pressure, said plunger being operable 100 to control the flow of pressure fluid by way of said connection.

3. A lubricator comprising, in combination with a chamber under fluid pressure, a 105 pump operable to force oil to said chamber against the action of the pressure fluid, said pump comprising a casing having a low pressure chamber and a high pressure chamber, a cylinder communicating with both of said chambers, a piston in said cylinder operable to draw oil from one of said chambers and force it into the other one of said chambers, a connection between the high pressure chamber and the chamber under pressure, a valve-controlled passageway between said chambers adapted to permit the passage of oil from the high pressure chamber to the low pressure chamber when the pressure of the oil in the high pressure chamber reaches a predetermined 110 degree, and a check valve in the connection between the high pressure chamber and the chamber under fluid pressure. 115

4. An oil pump comprising, in combination, a casing having two chambers in valve-controlled communication with each other, a cylinder communicating with both of said chambers, a piston operable in said cylinder to draw oil from one chamber and force it into the other, and a passageway leading 125 130

from the last mentioned chamber to a discharge outlet and intersecting said cylinder in its course, so that the flow of oil therethrough is controlled by the plunger in its movements.

5. An oil pump comprising, in combination, a casing having two chambers in valve-controlled communication with each other, a cylinder communicating with both of said chambers, a piston operable in said cylinder to draw oil from one chamber and force it into the other, and a passageway leading from the last mentioned chamber to a discharge outlet and having a circuitous path interrupted by said plunger, the latter having a port therethrough adapted to establish communication successively between separate portions of the passageway.

6. A pump comprising, in combination, a casing, a partition therein forming two chambers, a cylinder having an inlet connection with one of said chambers and an outlet connection with the other one of said chambers there being a check valve in said outlet connection a passage through said partition connecting said two chambers, a valve controlling the flow of oil through said passage, a plunger in said cylinder adapted to draw oil from one of said chambers and force it into the other, a discharge passage communicating with the last mentioned chamber, and a check valve in said passage.

7. A pump comprising, in combination, a casing having two chambers, a cylinder having an inlet connection with one of said chambers and an outlet connection with the other one of said chambers, there being a check valve in said outlet connection, a passage connecting said two chambers, a spring-controlled valve controlling the flow of oil through said passage, a plunger in said cylinder adapted to draw oil from one of said chambers and force it into the other, and a discharge passage communicating with the last mentioned chamber, said plunger being adapted to control the flow of oil through said discharge passage.

8. A lubricator comprising, the combination with a mechanism to be lubricated having a closed chamber under pressure and a moving part, of a pump comprising a casing having two chambers in valve-controlled communication with each other, a cylinder communicating with both of said chambers, a piston operable in said cylinder to draw oil from one chamber and force it into the other, a passage leading from the last mentioned chamber to the chamber of said mechanism to be lubricated, a pivoted rocker arm connected with said piston, and a lever connected with said arm and operatively associated with said movable part to actuate the pump.

9. A lubricator comprising, in combina-

tion with a chamber under pressure, of a pump for forcing oil into said chamber comprising a casing having in its opposite walls a pair of cylinders, and a pair of chambers each communicating with both of said cylinders, pistons in said cylinders operable to draw liquid from one of said pump chambers and force it into the other, discharge passages leading from the last mentioned chamber, a rocker arm pivoted at its center and connected at its opposite ends with said pistons, and an operating lever rigid with said arm and operable to rock it to actuate the pistons.

10. In combination with a chamber under pressure to be lubricated, a pump comprising a partitioned casing forming a high pressure chamber and a low pressure chamber, means for drawing oil from the low pressure chamber and forcing it into the high pressure chamber, a connection between the high pressure chamber and the chamber to receive lubrication, and a relief valve interposed between said high and low pressure chambers adapted to permit the return of oil to the low pressure chamber when the pressure in the high pressure chamber exceeds a predetermined degree.

11. In combination with a chamber under pressure to be lubricated, a pump comprising a high pressure chamber and a low pressure chamber, means for drawing oil from the low pressure chamber and forcing it into the high pressure chamber, a connection between the high pressure chamber and the chamber to receive lubrication, and a relief valve interposed between said chambers and the pump adapted to permit the return of oil to the low pressure chamber when the pressure in the high pressure chamber exceeds a predetermined degree, said passage connecting the high pressure chamber with the chamber to be lubricated being adapted to be controlled by the plunger in the movements thereof.

12. In combination with a chamber under pressure to be lubricated, a pump comprising a high pressure chamber and a low pressure chamber, means for drawing oil from the low pressure chamber and forcing it into the high pressure chamber, a connection between the high pressure chamber and the chamber to receive lubrication, and a relief valve interposed between said chambers and the pump adapted to permit the return of oil to the low pressure chamber when the pressure in the high pressure chamber exceeds a predetermined degree, said passage between the high pressure chamber and the chamber to be lubricated having a check valve therein.

13. An oil pump comprising, in combination, a casing having a low pressure chamber and a high pressure chamber, means for drawing oil from the low pressure chamber

and forcing it into the high pressure chamber, a discharge passage leading from the high pressure chamber and having a check valve therein, and a relief valve interposed between said chambers whereby to permit the oil in the high pressure chamber to flow to the other chamber when a predetermined pressure is attained in the high pressure chamber, each of said valves including springs and means for adjusting the tension thereof.

In testimony whereof, I have hereunto set my hand.

JOHN E. OSMER.
